FEED WATER HEATER

Charles J. Miller, South Nyack, N. Y., assignor to
The Superheater Company, New York, N. Y.

Substitute for application Serial No. 565,268, Sep-
tember 26, 1931. This application January 6,
1934, Serial No. 705,510

2 Claims. (Cl. 122—441)

The present invention is generally concerned with feed water heating systems associated with steam locomotives and pertains more particularly to a method of and means for returning the 5 condensate from the feed water heater to the tender tank.

In the majority of feed water heating systems for steam locomotives, the feed water heater is mounted on the front of the locomotive adjacent 10 the smoke stack above the water level of both the boiler and tender and a return pipe, which includes a check valve, interconnects the heater and tender. If the back pressure in the heater is below a predetermined value the check valve re- 15 mains closed and prevents any condensate from returning to the tender. Accordingly, an auxiliary device generally known in the art as a condensate return tank having suitable controlling mechanism is employed to open the valve with 20 the aid of compressed air acting on the surface of the water in the condensate return tank, provided the back pressure in the heater is inadequate to force the condensate through the valve for delivery into the tender tank.

Where the back pressure in the heater is above 25 a predetermined value, the check valve is open and the condensate from the heater, by reason of this back pressure, would be delivered into the tender tank without bringing into action 30 the pneumatically operated mechanism of the condensate return tank.

My feed water system in accordance with the present invention is a simplification of the systems heretofore employed in that a condensate 35 return tank and its equipment are eliminated and the condensate from the heater is returned to the tender by an injector disposed in the return connection between the heater and the tender. With the previous systems, the condensate 40 from the heater was returned to the tender by power from some other source other than the boiler feed pump and accordingly it is an object of the invention to utilize the power from the boiler feed pump to deliver the condensate to 45 the tender without employing a condensate return tank and its controlled mechanism.

In another aspect, the invention has for a further object the provision of an improved feed 50 water system of the character referred to in which the heater may be arranged on a low deck of the locomotive and disposed below the level of the water in the boiler and tender.

Other objects, advantages and features of the 55 invention will be best understood by reference to the following detailed description when con-

sidered with the accompanying drawing, in which

Fig. 1 discloses schematically my improved feed water system.

Fig. 2 is a fragmentary view of a system substantially identical with that of Fig. 1 except as to a valve appearing in each figure.

In carrying the invention into effect, the feed water heating system comprises a feed water pump A which draws water from the tender T 10 and forces it into the delivery conduit B past a weighted check valve C and into the heat exchange element D, the water being out of contact with the exhaust steam from the engine cylinders (not shown) or the pump A. The exhaust 15 steam is admitted into the closed feed water heater E, containing elements D, thru inlets, one of which appears at F, suitably connected to heater E. The check valve C is weighted to approximately 5 lbs. pressure and is designed to 20 prevent the head of water from the tender tank flooding the heater in the event of leakage through the pump, and this valve will only pass water thru elements D when under fluid pressure 25 from pump A.

The water circulating in the heat exchange element D is raised in temperature by the exhaust steam and is directed thru conduit G to the locomotive boiler H.

The exhaust steam is condensed in contacting 30 with the heat exchange element D and the condensate formed is delivered by gravity to the collector tank J through the condensate line K.

In open communication with the water delivery 35 conduit B is the pipe L which terminates in an open contracted portion M forming a water inlet for the injector pump, broadly denoted N.

Connecting the lowest part of the collector tank J and the injector N is condensate inlet pipe P which includes a valve Q for admitting the condensate from the collector tank J into the injector pump N. Whenever valve Q is open the water under pressure from the pipe L on its way into the flared portion or outlet R carries the condensate from pipe P with it into the return pipe S for delivery into the tender tank T. When closed, valve Q prevents water from tender tank T from backing up into the casing of heater E. The tank J, however, permits condensate formed in heater E to flow therefrom when valve Q is closed so as to prevent flooding and chilling of the heater E when pump A is not running. The heater E can therefore deliver hot water as soon as pump A starts up. Valve Q, of course, can be operated by any one of various known means, the 50 55 60 65 70 75 80 85 90 95 100

simple hand wheel shown being diagrammatic for the reason that the valve Q ordinarily will not be within the engine cab. I consider it within my invention to employ means to ensure that 5 valve Q shall open and close whenever the throttle of pump A is opened and closed.

It will be noted that the feed water heater is arranged considerably below the maximum water lever (indicated by dotted lines) of the tender. 10 The condensate from the heater and water from the tender under pressure by the operation of the pump are intermingled within the ejector casting, and consequently, the water returned to the tender is increased in temperature.

15 The apparatus illustrated in Fig. 2 differs from that of Fig. 1 in that Fig. 2 has an automatic valve Q_a instead of the hand operated valve Q of Fig. 1. As shown, valve Q_a is a check valve operating to pass liquid in the direction from tank J to 20 ejector pump N as indicated by the arrow alongside such valve Q_a . For this purpose, pipe P_a has a horizontal portion to permit using a check valve of the ordinary globe type.

The foregoing disclosure has been given by way 25 of example for purposes of illustration, and to bring out the underlying principles of my invention. Hence no unnecessary limitations should be understood and the appended claims should be construed as broadly as the state of the art permits.

30 This application is a substitute for my prior application, Ser. No. 565,268, filed September 26, 1931, for Feed water heaters.

What I claim is:

1. In a feed water system, the combination with a tender and feed water heater of the type in which steam is condensed out of contact with water, a conduit connecting the tender and heater, a pump disposed in the conduit for delivering water from the tender into the heater, the latter including means for admitting steam to heat the water circulating therethrough, a condensate return line, an ejector, a collector tank below 10 the level of said heater and in communication with said line and ejector to admit condensate from said heater into said ejector, valve means intermediate said tank and said ejector, a pipe connecting the conduit and ejector to supply feed water to the latter under super-atmospheric pressure wherein said last mentioned water and condensate are commingled, and means for directing the water commingled with said condensate back into the tender. 15

2. In an apparatus of the class described in combination, a collecting chamber for condensate liquid, an ejector having a source of pressure liquid and a discharge for the mixture of such liquid with the liquid pumped thereby, a tank into which 25 said discharge delivers and which may at times have a liquid level therein higher than said chamber, a pipe connection from said collecting chamber to said ejector, and a check valve in said pipe arranged to permit flow from said chamber to said injector but to prevent return flow from the injector to said chamber. 30

CHARLES J. MILLER.
